BOOM ANGLE INDICATOR FOR CRANES

Filed June 24, 1929

UNITED STATES PATENT OFFICE

ERICH H. LICHTENBERG, OF MILWAUKEE, WISCONSIN, ASSIGNOR TO KOEHRING COMPANY, OF MILWAUKEE, WISCONSIN, A CORPORATION

BOOM-ANGLE INDICATOR FOR CRANES

Application filed June 24, 1929. Serial No. 373,296.

The present invention deals with devices for indicating the working radius of a crane, and is a division in part of my co-pending application for patent, Serial No. 253,669, filed February 11th, 1928.

It is always desirable to obtain the maximum capacity from a machine, and in cranes or the like structures, if this maximum capacity is exceeded, the crane will overturn, causing a delay and possibly resulting in damage to the machine and operator thereof.

An object of my invention therefore, is to construct a simple device which is located on the boom of a crane or like structure, and indicates the working radius of the machine under varying working conditions.

In carrying out my invention, I make use of a pendulum suspended from the boom and actuated by gravity. The pendulum has indicia thereon, which indicate the working radius of the machine, both for different angular relations of the boom in respect to the body and for different inclinations of the body itself.

A further object of my invention is to provide means whereby the device may be adapted so as to correctly indicate the working radius of the machine for different lengths of booms.

Going more into detail, the pendulum comprises a body portion and an arm extending therefrom, the periphery of the body portion and arm taking an arcuate form. The pendulum is suspended or pivoted at the center of the arc so that rotation thereof within a circular casing or cover is possible without the pendulum striking against the cover. Indicia are carried on the periphery or arcuate portion of the pendulum and the cover is formed with a sight opening whereby the operator may see the indicia as they are brought before the sight opening.

In order to use my novel device with different lengths of booms, I propose to supply bands with different sets of indicia thereon which may be slipped over the pendulum member, the correct band being used according to the length of boom employed.

It is also important to note that when the machine body is swung about, the centrifugal

action increases the working radius, but this same action will affect the pendulum so as to indicate this increase.

For a full and more complete understanding of my invention, reference may be had to the following description and accompanying drawing, in which:

Figure 1 is a side elevation of a crane with my invention applied thereto, and showing in dotted lines the change in the working radius produced by an inclination of the body or a swinging of the body.

Figure 2 is a side view of my indicating device applied to a crane boom.

Figure 3 is an end view of the device shown in Figure 2 and has parts broken away to bring out the construction of the same.

Figure 4 is a perspective view of one of the interchangeable bands.

Like reference characters designate corresponding parts throughout the several figures of the drawings.

Referring to the drawings, A designates the swing body of a portable crane, B the traction support for the same, C the boom, and D the hoisting cable, all of conventional construction and well known in the art.

The indicator comprises the casing or housing composed of the base plate 10 having opposite apertured extensions 11 through which fastening members 12 are passed, and a cover member 13 removably secured to the base plate by means of the center bolt 14. Preferably the meeting edges of the cover and base plate are toothed or serrated so as to positively interengage and define a definite adjustment. This casing is secured to the side of the boom at a convenient point near its pivot so as to be within easy view of the operator standing upon the platform of the machine.

Within the casing on the bolt 14 is swung the pendulum member 15 which carries a tail-like extension 15' adapted to operate in relation to a window 16 in the casing cover 13. Upon the peripheral surface of this member suitable indicia 17 are provided, calibrated in proper order and terms representing the working radius. This calibration is necessarily based upon the angle of the boom rela-

tive to the surface of the ground and the length of the boom.

To enable my device to be applied to booms of different lengths I provide bands 18 as shown in Figure 4, each band being provided with suitable indicia 17 to properly indicate the working radius for a boom of a given length. Thus, when a longer boom is used, it is only necessary to remove the cover member and place the proper band over the pendulum member 15.

It will be apparent from the foregoing that as the boom is shifted upwardly or downwardly, the indicator member 15 will shift in relation to the window 16, owing to the tendency of the weight body to maintain its pendant position and by observing the indicia through the window the operator is always advised of the particular working radius.

20 When the machine is swung around, centrifugal force acts to extend the working radius but since this force obviously acts upon the pendulum or indicator member 15 to swing it around its support, a higher reading at the window 16 will be presented. Likewise, when the machine tips up, as shown in dotted lines in Figure 1, the reading changes upwardly, because the angle between the boom and the perpendicular line changes, 30 causing the rotation of the indicator member.

In the preferred form of my invention, the pendulum 15 will carry suitable indicia thereon, to properly indicate the working radius of the boom length most commonly employed, and the extra bands will be provided to adapt the device for use with other lengths of booms.

Having thus described my invention, what I claim as new and desire to secure by Letters 40 Patent of the United States, is:—

1. In combination, a boom hoist, means for adjusting the boom hoist, and indicator means carried by said boom hoist shiftable incident to adjustment of the hoist.

45 2. In combination, a boom hoist, means for adjusting the boom hoist, indicator means carried by said boom hoist shiftable incident to adjustment of the hoist, and means to adapt the indicator means for hoists of various lengths.

3. A material handling machine of the class described, comprising, in combination, a body, a boom supported thereby and adjustable in respect thereto, and indicator means carried by the boom, said means being shiftable incident to changes in inclination of the body.

4. A material handling machine of the class described, comprising, in combination, a swingable body, a boom carried thereby, and indicator means on the boom for indicating the working conditions of the machine prevailing during swinging of the body.

45 5. A material handling machine of the class described, comprising, in combination, a

swingable body, a boom carried thereby and adjustable in respect thereto, and indicator means carried by the boom, said means being adapted to indicate the working radius of the machine throughout the operation of the machine.

6. In a material handling machine, the combination, with a body and a boom carried thereby and adjustable in respect thereto, of a working radius indicator carried by the boom, said indicator comprising, a freely suspended member actuated by gravity and movable relative to a second member, and means for indicating the relative movement between the two members.

7. In combination, a boom hoist, means for adjusting the boom hoist, and a gravity actuated working radius indicator carried by said boom hoist.

8. In combination, a boom hoist, means for adjusting the boom hoist, and a gravity actuated working radius indicator carried by said boom hoist, said indicator comprising a pendulum, indicia on the pendulum, and a member having a sight opening therein for permitting the operator to view the working radius indicated thereby.

9. In a working radius indicator for cranes, the combination, with a member having indicia thereon, of means for replacing said indicia thereby adapting said member to be used with booms of varying lengths.

In testimony whereof I affix my signature.

ERICH H. LICHTENBERG.
